COMBINATION LADDER AND FRUIT LOWERER

Ernest H. Warner, Nova, Ohio

Application August 2, 1954, Serial No. 447,291

3 Claims. (Cl. 228—1)

The present invention relates to a combination ladder and fruit lowerer and has for an object the provision of a device of this kind which is capable of being quickly and easily transported to its place of use and firmly held against accidental displacement therefrom.

Another object of the present invention is to provide a structure of this character in which the mast or ladder can be quickly adjusted to various heights and inclinations within the limits of the device with respect to a tree.

A further object of the present invention is to provide in a device of this type means under the control of the workman for permitting the workman to change his position with respect to the tree independently of the mast adjustment.

A still further object of the present invention is to provide a device of this kind in which the mast and the operator supporting member carried by the mast can be collapsed to substantially flat condition upon the base or supporting platform in order to facilitate the movement of the device from place to place.

The present invention aims to provide a combination ladder and fruit lowerer in which means are provided for holding the operator supporting member in its adjusted position on the mast.

The present invention also aims to provide a device of this type into which means are incorporated for adjusting the device to compensate for uneven terrain.

The present invention contemplates the provision of a device of this character in which the mast is detachably mounted on the base and means are provided for retaining the mast against accidental removal from the base.

The present invention also contemplates the provision of a combination ladder and fruit lowerer which can be operated easily by one man and by the use of which an increased number of boxes of fruit can be picked in a given time as compared to the old method and means.

With the foregoing and other objects in view, the invention will be hereinafter more fully described and more particularly pointed out in the appended claims.

In the drawings in which the same parts are denoted by the same reference numerals throughout the several views,

Figure 1 is a side elevational view of a device constructed in accordance with the present invention and shown in one of its raised operative positions and with parts broken away and parts in section,

Figure 2 is a rear elevational view of the same,

Figure 3 is a side elevational view of the device in lowered inoperative position ready to be moved to a new location,

Figure 4 is a top plan view of the same with parts broken away,

Figure 5 is a fragmentary sectional view taken on the line 5—5 of Figure 4,

Figure 6 is an enlarged fragmentary elevational view of the elevator or operator supporting member,

2

Figure 7 is a sectional view taken on the line 7—7 of Figure 6,

Figure 8 is a sectional view taken on the line 8—8 of Figure 1,

Figure 9 is an enlarged perspective view of the lowering chute, and

Figure 10 is an enlarged sectional view taken on the line 10—10 of Figure 9.

Referring more particularly to the drawings, 10 generally indicates a base frame comprising a transversely extending rear axle housing 11, a pair of side pieces 12 and intermediate transverse braces 13 and 14.

The side pieces 12 are made of hollow tubing or solid rods and have their rear ends secured as by welding 200 or the like to the housing 11 adjacent its opposite ends. From their points of attachment to the housing the side pieces extend forwardly in converging relation and the forward end portions 12a of the side pieces converge more sharply and have their forward end portions joined by a connecting member 15.

A post 16 has its upper end secured as by welding 201 or the like to the connecting member 15 and its lower end carries a foot 17 from which depends a pair of prongs 18 for penetrating the ground and a flat ground engaging surface 19. A split ring 20 has its free end secured by welding 202 or the like to the portions 12a of the side pieces 12, as indicated at 21. The brace 13 has its opposite ends secured by welding 203 or the like to the pieces 12 and portions 12a at their points of juncture and the opposite ends of the brace 14 are connected in a similar manner to the pieces 12.

An axle 22 extends through and is supported by the housing 11 and has its opposite end portions projecting beyond the opposite ends of the housing. Each of the projecting end portions of the axle 22 has fixed thereto a ground wheel 23. Means are associated with each wheel for adjusting the device to compensate for unevenness of the ground and to prevent accidental movement of the device when in use. Each of these means comprises a standard 24 which may be in the form of a rack bar having a foot 25 for engaging the ground 26 and each foot 25 may have a pair of prongs 27 for penetrating the ground and a flat ground engaging surface 28.

Each standard may be non-circular in cross section, for example, square or rectangular, and has a set of vertically arranged teeth 29 extending from one side thereof.

A gear box, generally indicated at 30, is associated with each standard 24 and is secured to the adjacent portions of the housing 11 by welding 204 or the like. Each gear box comprises an elongated guide portion 31 having a through bore 32 of a size and shape substantially conforming to that of the standard 24 to permit vertical sliding movement of the standard in the guide portion, but to prevent rotation thereof. Each gear box also comprises an offset portion 33 housing a pinion 34 which cooperates with the teeth 29 of its associated standard to comprise a rack and pinion arrangement for the raising and lowering of the feet 25.

Each pinion 34 is fixed to and rotated by an adjusting rod 35 which extends through suitable aligned openings in the front and rear walls of the offset portion 33.

Each rod 35 extends forwardly above its associated side piece 12 through a suitable opening in a supporting guide 36 which is carried by its associated side piece and extends through a suitable opening in the adjacent enlarged end portion 37 of a cross bar 38 which extends over and is secured to the forward end portions 12a. The forward end portion of each rod terminates adjacent the forward end of the device in a crank handle 39.

In order to hold each standard 24 in its adjusted position, an arm 40 secured to each side piece 12 by weld-

ing 205 or the like extends outwardly therefrom and terminates in an enlarged free end portion 41 provided with an aperture through which the adjacent rod 35 rotatably extends. A pinion 42 is rotatably carried by the enlarged portion 41 of each arm and is fixed to its rod 35. A lever 43 is pivotally mounted as at 44 intermediate its ends to each arm and at one end carries a pawl 45 which cooperates with the pinion 42 to prevent rotation of the rod in a direction to effect raising of the standard 24.

The opposite end portion 46 of the lever 43 is enlarged and has a lower flat bearing surface 47 from which depends a guide pin 48, the lower end portion of which extends through the horizontal flange of an angle iron shaped bracket 49. A coil spring 50 encircles the pin and has its opposite ends engaging the bearing surface 47 of the lever 43 and the horizontal flange of the bracket 49 to urge the end portion 46 of the lever 43 upwardly to cause the pawl to engage the teeth of the pinion and prevent retrograde movement of the rod 35. In order to retain the spring 50 and the pin 48 in proper relative position and to limit the upward movement of the end portion 46 of the lever, the lower end portion of the pin 48 is provided with a suitable opening through which extends a cotter pin 51 and a washer 52 is interposed between the cotter pin and the horizontal flange of the bracket.

A pair of brackets or lugs 53 are secured as by welding 206 or the like to the upper faces of the side pieces 12, the portions 12a and the brace 13 at their points of juncture. The brackets are spaced apart and each has a vertical series of rearwardly opening recesses 54 formed therein for removably and selectively receiving the opposite end portions of a pivot pin 55 carried by the runners 56 of a mast or ladder generally indicated at 57.

In order to retain the end portions of the pivot pin 55 within the recesses 54 of the brackets 53, a locking cap 58 is removably associated with each bracket 53. Each locking cap 58 removably fits over its bracket and comprises a pair of side walls 59 joined by end walls 60 to define a space for the reception of the bracket 53. Each side wall has a downwardly opening socket 61 therein defined by a pair of legs 62 as can be seen in Figure 1 of the drawings. When the locking cap 58 is slid down over the bracket and pivot pin 55 with the legs 62 straddling the pin, one of the legs 62 of each pair of legs will prevent the pin 55 from accidentally escaping from the recess 54 in the bracket 53. However, when it is desired to separate the mast 57 from the base frame 10, the caps 58 may be slid upwardly until the legs 62 are clear of the pivot pin 55.

The runners 56 of the mast 57 may be of channel shape in cross section having vertical flanges 56a, bottom horizontal flanges 56b and top horizontal flanges 56c and the vertical flanges or closed sides face outwardly and their open mouths face inwardly. The runners are joined together and braced by a series of longitudinally spaced apart rungs or braces 63 and extend rearwardly from their points of pivotal attachment to the brackets 53.

A yoke, generally indicated at 64, comprises a pair of arms 65 and 65' having flat straight portions 66 and 66', converging portions 67 and 67' disposed at an angle to the longitudinal axis of the portions 66 and 66' and straight flat free end portions 68 and 68'. The flat portions 66 and 66' engage the outer faces of the vertical flanges 56a of the runners 56 adjacent the upper end thereof and have suitable openings for receiving therethrough the opposite screw threaded end portions of a rod 69 upon which nuts 70 are removably threaded to removably hold the yoke upon the ladder 57. In order to help secure the yoke in position, pins 71 are carried by the vertical flanges 56a of the runners and are extended through suitable openings formed in the arms 65 and 65'. The end portions 68 and 68' of the yoke are spaced apart and receive therebetween a pulley 72 mounted on an axle 73 which extends through suitable holes in the

portions 68 and 68' and a cable guide 74 is mounted on the extended portions of the axle.

A cable 75 is entrained over the pulley 72 and the free end portion of the lower run of the cable is secured to a bail 76, the opposite end portions of which are secured in any suitable manner to the opposite sides 77 of a gear box 78. The sides 77 of the gear box are joined by a bottom 80 which is secured to the sides by welding 207 or the like. The lower end portion of each side 77 is bent outwardly at substantially right angles to form a guide flange 81 which is received in the spaced defined by the horizontal flange 56c of the runner 56 and the horizontal flange 82 of an elongated guide member 83 of angle iron shape in cross section, the vertical flange 84 of which is secured to the inner face of the vertical flange 56a of the runner 56. The lower end of the guide space is closed by an abutment 56d which is secured to the runners 56 and the guide member 83.

The opposite end portion of the cable 75 is secured to a drum 85 about which the cable is adapted to be wound and unwound. The drum 85 has a square shaped bore therethrough which frictionally receives the intermediate square shaped portion of a shaft 89 having its opposite end portions rounded and extending into suitable openings in gear frame or retaining walls 77a and 77b welded at 208 to a cross brace 118 and the bottom 80 of the gear box 78 so that the drum 85 is rotatably supported by the walls 77a and 77b.

A large gear wheel 91 is fixed to one end portion of the shaft 89 by a pin 92 which extends through a suitable hole in the hub 93 of the wheel 91. On the other portion of the shaft 89 there is fixed thereon a brake drum 94 partially encircled by a brake band 95, one end of which is anchored to the adjacent wall 77a by being looped as at 96 about a fastening element 97 which is secured to the adjacent wall 77a. The opposite end of the band 95 is secured to a pin 98 by being looped thereabout as at 99. The pin 98 rides in an arcuate shaped slot 100 formed in the adjacent wall 77a to guide it in its movements when depressed by the foot of the operator. The pin 98 returns to its inoperative position under the influence of a spring 101.

The large gear wheel 91 meshes with a smaller gear wheel 104 fixed by a pin 105 which extends through a suitable opening in the hub 106 of the wheel 104 to a crank shaft 107 having a pair of spaced apart crank pedals 108. The opposite end portions of the crank shaft extend through and beyond the sides 77 of the gear box 78. In order to prevent lateral movement of the crank shaft 107, a collar 109 is placed on one extended end portion of the crank shaft and cotter pins 110 are received by suitable holes in the opposite extended end portions of the crank shaft. A collar 111 is disposed on the crank shaft between the adjacent cotter pin 110 and the adjacent side 77 of the gear box. Spacing sleeves 112 and 113 encircle the crank shaft between the crank pedals 108 and the adjacent sides 77 of the gear box and are secured by welding 209 or the like to the lower end portions of an inverted substantially U-shaped frame member 114 of a fruit box, generally indicated at 115. Each crank pedal 108 is separate from the main portion of the shaft 107 and is detachably secured thereto by providing a screw threaded socket in each end of the shaft 107 for receiving a screw 107a which extends through a suitable opening in the crank pedal 108.

The frame member comprises a pair of downwardly extending slightly diverging legs 116 and an arcuate shaped connecting portion 117 joining the upper ends of the legs. The lower end portions of the legs 116 are substantially parallel and are secured to the inner faces of the sides 77 of the gear box by welding 210 or the like. The cross brace 118 has its opposite ends secured to the legs 116. A second frame member, generally indicated at 119, is spaced rearwardly from the frame member 114 and is of substantially the same shape as the frame mem-

ber 114 having an arcuate shaped connecting portion 120 and downwardly extending diverging legs 121, the lower end portions of which are substantially parallel to one another and are secured by welding 211 or the like to the inner faces of the sides 77 of the gear box. A cross brace 122 is secured to the lower end portions of the legs 121 and carries a hook 123. The hook is pivotally mounted on the cross brace by an eye 124 and extends therefrom outwardly through the adjacent open end of the gear box and terminates in a bent free end portion 125 for selectively engaging a rung 63 of the ladder 57 for assisting the brake band 95 in holding the gear box and fruit box in its adjusted position on the ladder.

The fruit box also comprises a covering, generally indicated at 126, having a substantially arcuate shaped top 127 conforming to the shape and size of the connecting portions 117 and 120 of the frame members and secured thereto in any appropriate manner, downwardly extending converging side walls 128 and a substantially arcuate shaped bottom 129 of smaller radius than that of the top 127. The legs 116 and 121 of the frame members extend through suitable openings formed in the covering at points where the top and side walls of the covering join one another. The lower or discharge end 130 of the covering 126 is open and the bottom 129 is inclined towards the top 127 as it approaches the open discharge end 130.

The open discharge end of the covering is closed during the fruit picking operation by a skirt 131 which may be made of some flexible but sturdy material, such as, canvas. One open end portion of the skirt 131 encircles the discharge end portion of the covering 126 and is held thereon by a clamping ring 132 having apertured ears 133 for receiving a screw threaded bolt and wing nut 134 so that the clamping ring may be tightly clamped around the skirt and discharge end portion of the covering.

The other open end portion of the skirt 131 will be gathered as at 131a and inserted into a clamping device, generally indicated at 135, which comprises an L-shaped lever 136 pivotally connected adjacent one end as at 137 to the free end portion of the horizontal leg of an L-shaped bracket 138. The horizontal leg of the lever 136 extends over the horizontal leg of the bracket in spaced apart parallel relation thereto and its free end portion is provided with a suitable opening for receiving the upper screw threaded portion 139 of the vertical leg of the bracket. A nut 140 is received by the screw threaded portion 139 so that the lever 136 can be brought into frictional engagement with the gathered portion 131a of the skirt to securely clamp the gathered portion of the skirt in closed condition within the clamping device.

The upper or inlet end of the covering 126 is closed by a wall 141 provided with an opening 142 which frictionally supports a funnel 143 having a flared mouth 144 through which the picked fruit may be inserted into the fruit box 115. An outwardly facing shoulder 142a engages a portion of the inner end of the funnel 143 to help support it. In order to prevent the fruit from becoming bruised upon entering the fruit box, a series of interrupters 145 are disposed in the downward path of travel of the fruit from the funnel towards the skirt 131.

These interrupters are secured to enlarged end portions 146 which are welded as at 212 to supporting bars 147, the opposite ends of which are secured to the side walls 128 of the covering 126. The interrupters are formed of a material, such as rubber or the like, that is of such a character that they will flex to the dotted line position shown in Figure 6 of the drawings under the influence of the descending fruit, but are capable of automatically returning to the full line position of Figure 6 when relieved of the influence of the fruit. The interrupters are of such a size and shape that their free edges engage the side walls 128 and bottom 129 of the covering 126 so that the fruit cannot pass freely between the side walls and bottom and the free edges of the interrupters.

In Figures 9 and 10 is shown a fruit picker 148 which may be attached to the funnel 143. The picker comprises a tubular member 149 of flexible material, such as canvas or the like. A reinforcing ring 150 is carried by the lower end portion of the tubular member by folding the free end portion of the member over the ring and stitching the folded over portion to the tubular member as at 151. The upper end portion of the tubular member is flared outwardly, the flare being greater on one side than the other as indicated at 152. A substantially V-shaped in cross section knife 153 of metal or the like is mounted in the flared upper end portion of the tubular member and comprises a cutting plate 154 having a V-shaped cutting notch 155, a downwardly and inwardly inclined side wall 156 and a depending flange 157 forming a reinforcing ring. The upper end portion of the tubular member is shaped to the knife 153 and the corresponding parts of the knife and upper end portion of the tubular member are secured together in any suitable manner, such as by adhesive or the like.

It will be noted that the upper end portion of the tubular member terminates short of the cutting edge of the knife plate 154 so as not to interfere with the cutting of the fruit stem by the knife. In order to prevent the fruit from striking the hard metal surface of the side wall 156 and ring 157, a layer 158 of material, such as canvas or the like, is secured to the side wall and ring by a suitable adhesive and its lower end portion is secured to the tubular member by a row of stitching 159.

30 A handle 160 carries at one end a plate 161 which is secured to the side wall 156 of the knife 153 by rivets 162 or the like. Adjacent its opposite free end, the handle 160 carries a staple 163 and the tubular member carries a staple 164. A link 165 is pivotally connected to the staples 163 and 164 by the eyes 166 at opposite ends of the link.

A seat 167 is adjustably mounted on the upper rearward portion of the fruit box. The seat is secured to a cross bar 168 having an arm 169, depending from each 40 end thereof. A crank shaped link 170 has one end secured by a rivet 171 or the like to each arm and adjacent its opposite end it carries a screw threaded guide pin 172 which rides in a curved slot 173 formed in a plate 174 secured to the outer face of the covering. A 45 wing nut 175 is received by each pin 172 and when screwed home binds against the plate 174 to hold the seat in its adjusted position. A brace 176 has one end rigidly secured to the seat and its opposite end portion formed into an eye 177 which receives a pivot pin 178 50 carried by a lug 179 secured to the wall 141 of the covering 126.

In order to raise and lower the mast 57, there are provided a pair of pneumatic devices, generally indicated at 180, each of which comprises a piston 181 working 55 in a cylinder 182 and a piston rod 183 having its lower end connected to the piston and its upper end portion projecting from the cylinder. The extreme upper end portion of the piston is flattened as at 184 and is apertured to receive the screw threaded projecting end portion of a bolt 185 carried by the runners 56 of the ladder 57. A nut 186 is received by the threaded projecting end portion of the bolt to detachably secure the piston rod to the ladder 57. A substantially L-shaped arm 187 has one leg secured to the bottom of the cylinder by a rivet 188 or the like and its other leg pivotally connected as at 189 to an upstanding bracket 190 which is secured by welding 213 or the like to the housing 11.

A hand pump 191 which may be a bicycle tire pump or the like is secured to the covering 126 by a pair of clamps 192 adjacent to the seat so that the piston rod handle 193 and the relief valve handle 194 are within convenient reach of the operator. A hose 195 leads from the lower end of the pump cylinder 196 to a connector 197 which connects the hose 195 to two branch

hoses 198. The branch hoses are connected to the lower ends of the pneumatic cylinders 182.

In the use of the device, assuming that it is in its lowered position shown in Figures 3 and 4 of the drawings, the device will be attached by the ring 20 to the draw bar of a tractor and transported to the orchard where it is to be used. The draw bar will be uncoupled and the feet 25 will be brought into engagement with the ground by operating the rods 35 so as to level the base frame 10 and to hold the device steady against accidental movement. The pneumatic devices 180 will be operated to raise the mast to the desired height and inclination and the operator will then mount the seat 167. Operation of the crank shaft 107 by means of the pedals 108 will cause the cable 75 to wind upon the drum 85. This will draw the elevator which comprises the gear box and the fruit box up the mast until the desired position has been attained, for example, that shown in Figures 1 and 2 of the drawings. The operator will press the pin 98 with one foot to apply the brake band 95 to the brake drum 94 against the action of the spring 101 to hold the elevator in its adjusted position. The operator will then pick the fruit and drop it into the funnel 143 until the covering 126 is filled.

The operator will release the hook 123 from engagement with the bolt 185 or the rung 63 with which it is engaged and release the brake and lower the elevator by reversing the movement of the crank shaft 107 and gently apply the brake so as to lower the supporting means at a safe and reasonable speed. When the elevator has reached the lower end of the ladder the abutment 56d will prevent the escape of the elevator from the runners 56. A fruit box will be placed upon the base frame 10 adjacent the lower end of the covering 126 and the gathered portion 131a of the skirt 131 will be released from the clamping device 135 and the fruit discharged into the fruit box from the covering 126. The gathered portion 131a will then be replaced in the clamping device and the fruit picking operation repeated. The inclination of the ladder to the horizontal may be adjusted between about sixty degrees to eighty-five degrees.

When the device is used for picking fruit from trees having closely knit limbs, such as the orange tree, in which case it is difficult to reach the fruit, the fruit picker 148 may be used. The lower end of the tubular member 149 is forced into the upper end of the funnel 143 and due to the ring 150 will have a frictional fit therein. The operator will grasp the handle 160 and move the flared end portion of the member 149 toward the fruit until one of the fruit is disposed in the open mouth 198 with the stem received by the cutting notch 155. Movement of the member 149 toward the operator will sever the stem and the fruit will fall into the covering 126.

The device can be moved from tree to tree by raising the feet 25 until the wheels 23 engage the ground and lifting the foot 17 and rolling the device on its wheels 23.

When it is desired to move the device to another orchard, the mast 57 will be lowered by turning the relief valve handle to open position, nuts 186 removed and the piston rods 183 removed from the bolt 185, the locking caps 58 removed and the pivot pins withdrawn from the recesses 54. The ladder 57 will be placed upon the base frame 10 between the lugs 53 as shown in Figures 3 and 4. One person may then move the device by the ring 20 or it may be hitched to a trailer. The locking caps 58 may be replaced on the lugs 53 for safe keeping.

The independent adjustment of the feet 27 will permit leveling of the device when it is used on uneven terrain and the pawl 45 and pinion 42 latching arrangement will positively hold each foot in its adjusted position. The post 16 may be made in the form of two telescopic sections with a vertical series of holes in one section and a hole in the other adapted to be brought selectively into

registry with the series of holes and a locking pin to be inserted through the registered holes.

In addition to picking fruit, the device may be used for many other purposes where a ladder is required, such as, in pruning trees.

All of the rigid parts of the device may be made of aluminum or steel or other suitable material.

It is obvious that various changes and modifications may be made in the details of construction and design of the above specifically described embodiment of this invention without departing from the spirit thereof, such changes and modifications being restricted only by the scope of the following claims.

What I claim is:

1. A combination ladder and fruit lowerer comprising supporting means, a mast movably carried by said means, means on said supporting means and connected to said mast for moving said mast selectively to various positions of elevation between an extreme lowermost position and an extreme elevated position, a support for an operator mounted on said mast for movement relative thereto, fruit lowerer means carried by said operator support, and means for moving said operator support longitudinally of the mast comprising a drum rotatably mounted on said operator support, a pulley on said mast, a cable entrained over said pulley and having one end secured to the drum and its other end secured to said operator support, and manually operated means on said operator support for rotating said drum, thereby to cause said cable to wind upon the drum and move the operator support along the mast, and brake means carried by said operator support for preventing rotation of said drum.

2. A combination ladder and fruit lowerer comprising supporting means, a mast movably carried by said means, means on said supporting means and connected to said mast for moving said mast selectively to various positions of elevation between an extreme lowermost position and an extreme elevated position, a support for an operator on said mast, fruit lowerer means carried by said operator support, said supporting means comprising ground engaging wheels, ground gripping leveling feet on said supporting means, means on said supporting means and connected to said feet for selectively bringing the wheels and feet into their operative positions, and cooperating means on said supporting means and feet for independently adjusting each foot with respect to the supporting means.

3. A combination ladder and fruit lowerer comprising supporting means, a mast movably carried by said means, means on said supporting means and connected to said mast for moving said mast selectively to various positions of elevation between an extreme lowermost position and an extreme elevated position, a support for an operator on said mast, fruit lowerer means carried by said operator support, said mast removably pivotally mounted on said supporting means, and removable means retaining said mast pivotally mounted on the supporting means and for permitting removal of the mast from the supporting means comprising a bracket on the supporting means having a socket opening through one edge thereof, a pivot pin on the mast removably received by the socket, and a locking cap removably fitted over the bracket to mask the socket and retain the pivot pin therein.
